FUSE TONGS

Filed Aug. 31. 1926

Patented Apr. 24, 1928.

1,667,332

UNITED STATES PATENT OFFICE.

LESTER L. STAHLER, OF UNION CITY, INDIANA.

FUSE TONGS.

Application filed August 31, 1926. Serial No. 132,829.

This invention relates to tongs for placing and removing fuses, these tongs being used for handling fuses in electrical plants where voltages are very high and where the fuse 5 boxes are often times disposed at a considerable height above the floor, though often the fuse is at a height approximately the same as that of the operator.

The general object of the present invention 10 is to provide a fuse tongs which is capable of use whether the fuse be at a height above the operator or approximately at the same height as himself and further to provide a fuse tongs having two separate jaws hinged 15 to each other with screw-threaded means operable by the handle whereby the jaws may be closed or opened.

A further object is to so connect the wooden jaws to the jaw operating and supporting 20 means that the jaws may open and close freely at any angle to thus permit the device to be used under a large variety of circumstances.

My invention is illustrated in the accompanying drawings wherein:—

Figure 1 is a perspective view of my improved fuse tongs;

Fig. 2 is a side elevation of the same;

Fig. 3 is a transverse section through the 30 jaws.

Referring to these drawings it will be seen that the jaws 10 are complementary to each other and each jaw is formed of a relatively flat slab of wood with two inwardly projecting confronting ribs 11, the rib having a semi-circular recess 12. These jaws are jointed by flat hinges 13, these hinges being formed each by a strip of strap iron extending across the back of the member 10 and then angularly bent and hinged to each other at 14 by means of the usual pintles. The shank or staff 15 upon which the jaws are mounted has a ferrule 16 and a metallic head 17 having a screw-threaded shank 18. The head 17 is reduced in diameter to provide a shoulder 19 and resting upon this shoulder is a collar 20 provided with opposed lugs. Links 21 are pivoted to these lugs.

The screw 18 passes through the apex of 50 an approximately V-shaped yoke 22, the extremities of which are outwardly turned and formed to pivotally engage with lugs 23 which are formed upon the arms 24. The inner ends of these arms are pivotally connected to the links 21. The ends of the arms are inwardly turned at 25 and each is formed

with a ball 26 received within a socket 27 mounted upon the outer face of the corresponding jaw.

As will be seen from Figure 2, the jaws 10 may be tilted into any desired angle to the plane of the yoke 22 and by rotating the handle 15, the jaws may be closed or opened and inasmuch as the jaws are mounted upon the levers or arms 24 by means of the ball 26 and socket joints, the jaws may take any angular relation to the levers which may be required. By adjusting the handle clockwise the jaws will close tightly and by twisting the handle counterclockwise, the jaws will open 70 the ball and socket joints and permit the jaws to open or close freely at any angle desired, thus doing away with the necessity of using two different forms of tongs, one for use where the fuse is disposed approximately 75 at the same height as the operator and the other where the fuse is disposed above the operator's head.

I claim:—

1. A fuse tongs comprising a handle, opposed jaws, the jaws being hinged to each other, a yoke having a screw-threaded opening, a screw mounted upon the handle and extending through the screw-threaded opening of the yoke, levers pivoted to the yoke 85 having their outer ends each engaged with a corresponding jaw by a universal joint, and links operatively connecting the inner ends of the levers to the handle but permitting the rotation of the handle relative to said levers. 90

2. A fuse tongs comprising a handle, opposed jaws, the jaws being hinged to each other, a yoke having a screw-threaded opening, a screw mounted upon the handle and extending through the screw-threaded opening of the yoke, levers pivoted to the yoke having their outer ends each engaged with a corresponding jaw by a universal joint, and links pivotally connected to the ends of the levers, and a collar rotatably mounted 100 upon the handle at its upper end and to which the links are pivotally connected.

3. A fuse tongs comprising a handle having a cylindrical head and a screw-threaded shank, a pair of jaws hinged to each other, an approximately V-shaped yoke having screw-threaded engagement with the shank and having its ends outwardly turned, a pair of levers pivoted to the outwardly turned ends of the yoke, a collar loosely surrounding the head, links pivotally connecting the collar and the levers, and ball and socket 110

joint connections between the outer ends of the levers and the jaws.

4. A fuse tongs including opposed jaws, hinge members attached to the jaws and pivotally engaged with each other whereby said jaws may be turned into or out of a parallel position, a pole constituting a handle, means for swivelly supporting the jaws upon the pole and permitting the jaws to move toward or from each other, and means for moving the jaws toward or from each other including interengaging screw-threaded elements, one mounted upon the handle pole and the other operatively connected to the jaws whereby a rotation of the handle pole will act to shift the jaws toward or from each other.

5. A fuse tongs including opposed jaws, hinge elements attached to the jaws and pivotally engaged with each other whereby the jaws may be shifted toward or from a parallel position, a handle pole, arms, one for each jaw, each jaw having a universal joint connection with the corresponding arms, means for swivelly supporting the arms upon the handle pole, a member engaging said arms and acting when shifted in one direction to close the arms and jaws and when shifted in the other direction to open the arms and jaws, and a screw-threaded member carried by the handle pole and having screw-threaded engagement with said member on the jaw arms to cause the jaw arms to shift in one direction or the other as the handle pole is rotated.

totally engaged with each other whereby the jaws may be shifted toward or from a parallel position, a handle pole, arms, one for each jaw, each jaw having a universal joint connection with the corresponding arms, means for swivelly supporting the arms upon the handle pole, a member engaging said arms and acting when shifted in one direction to close the arms and jaws and when shifted in the other direction to open the arms and jaws, and a screw-threaded member carried by the handle pole and having screw-threaded engagement with said member on the jaw arms to cause the jaw arms to shift in one direction or the other as the handle pole is rotated.

In testimony whereof I hereunto affix my signature.

LESTER L. STAHLER.
